UNITED STATES PATENT OFFICE.

RUDOLPH G. BEKER, OF PITTSBURG, PENNSYLVANIA, ASSIGNOR OF TWO-THIRDS TO FREDERICK H. KINDL, OF PITTSBURG, PENNSYLVANIA.

UPSETTING-MACHINE.

SPECIFICATION forming part of Letters Patent No. 733,898, dated July 14, 1903.

Application filed March 1, 1902. Serial No. 96,240. (No model.)

To all whom it may concern.

Be it known that I, RUDOLPH G. BEKER, a resident of Pittsburgh, in the county of Allegheny and State of Pennsylvania, have invented a new and useful Improvement in Upsetting-Machines; and I do hereby declare the following to be a full, clear, and exact description thereof.

My invention relates to metal-upsetting-machines, and more especially to that class of machines in which hot metal rods are fed to the machine either automatically or by hand, cut into exact lengths while in the heated state, and then upset for the purpose of forming rivets, bolt-blanks, pins, and the like.

One of the objects of my invention is to provide a machine of this character with means whereby one, two, or more bars are automatically fed into the machine in order to make one, two, or more upset articles at a single stroke of the upsetting-punch.

A further object of my invention is to provide means whereby the stock-gage, the gripping-dies, and the upsetting-punch can be adjusted without stopping the machine.

In most prior machines of this kind only a single stock-rod could be fed to the machine at a time, so that only a single rivet, bolt, or other blank could be produced at one stroke of the machine. Furthermore, the stock-gage, gripping jaws or dies, and heading or upsetting punch could be adjusted only while the machine was at rest, thus making it necessary to frequently stop the machine and greatly decreasing the output. While in my machine the general arrangement for feeding the bars to the machine, cutting the same into sections, and upsetting the same does not differ essentially from present machines, the improvements above referred to enable the output to be increased three or four times over prior machines without increasing the speed of the machine.

In the accompanying drawings, Figure 1 is a longitudinal vertical section of my machine. Fig. 2 is a horizontal section of the same. Figs. 3 and 4 are cross-sections on the line 3-3, Fig. 2, showing the gripping-dies in closed and open positions, respectively. Fig. 5 is an elevation of the front end of the machine. Fig. 6 is a front view of the upsetting-punches.

Fig. 7 is a sectional detail showing the manner of mounting one of the feeding-rollers. Fig. 8 is a transverse section through the head carrying the upsetting-punch; and Figs. 55 9, 10, and 11 are horizontal sections through the gripping and shearing dies, showing the same in three different positions.

My machine does not deviate in general construction from present machines, and it is provided with the usual cutting and gripping-dies, reciprocating upsetting-punch, feeding means, stop-gage, and suitable mechanism for operating these parts. The machine is provided with the frame 1, which carries at its forward end the rod-feeding rolls 2 and 3 and is preferably placed in front of a heating-furnace 4, from which the hot rods are fed to the machine. In the frame near its forward end is mounted a plate 5, having openings 6 therethrough, through which the stock-rods pass. This plate serves as the stationary jaw of the shears and preferably has the openings therethrough beveled toward the front, as shown. In proximity to this shearing-plate are the stationary gripping jaw or die 7 and the movable gripping jaw or die 8, the latter being mounted close to the face of the plate 5 and adapted to pass across the openings 6 therein, so that it will cut off the stock-rod and carry the cut-off piece over sidewise and against the stationary gripping-die 7. The stock-gage is shown at 9 and the heading-punch at 10, the latter being secured to a head 11, which is mounted to reciprocate in ways 12 in the frame, and being actuated by any suitable mechanism—such, for instance, as the connecting-rod 13, pivoted to said head at one end and having its other end connected to the crank or eccentric 14 on a horizontal shaft 15, mounted in the outer end of the frame. This shaft 15 is provided with a fly-wheel 16 and will be driven from any suitable source and in any suitable way. Mounted in bearings on the side of the frame 1 is a horizontal shaft 17, which is driven from the shaft 15 by the bevel-gears 18, and which is provided with a crank or eccentric 19, to which is secured one end of a connecting-rod 20, the other end of which is connected to the joint of the toggle-links 21, by means of which the movable gripping-die 8

is actuated. The feed-rollers 2 and 3 are secured to the upper end of shafts 23 and 24, having at their lower ends beveled pinions 25 and 26, which mesh with beveled pinions 27 and 28 on a horizontal shaft 29, which is connected by means of the vertical shaft 30 and beveled pinions 31 and 32 to the shaft 17. Thus all parts of the machine are actuated from the single drive-shaft 15. All of the parts so far described are or may be of the usual type and form no part of my invention, and the exact arrangement, especially of the driving-gearing, may be departed from without affecting the principle of my invention.

15 The first part of my invention consists in so constructing the machine that a plurality of stock-rods can be simultaneously fed to the machine and cutoff and upset at a single stroke. To this end the feed-rollers 2 and 3 are vertically disposed, as shown, and are provided on their peripheries with a plurality of grooves 33, two such grooves being shown, although a larger number may be provided. By means of these two grooves 25 two stock-rods 34 can be simultaneously fed to the machine. The shearing-plate 5 is provided with as many openings 6 as there are stock-rods, two such openings being shown in the present case, said openings being one 30 above the other. So, too, the gripping-dies 7 and 8 will be provided with a corresponding number of gripping-cavities 35, and the head 11 will carry a corresponding number of upsetting-punches 10, said punches being placed one above the other, as shown. While 35 the vertical arrangement shown is not absolutely essential, still it is preferable, as by this means the plurality of upset blanks will generally drop out of the gripping-dies of 40 their own accord as soon as the latter are opened, whereas if a horizontal arrangement were employed some ejector or knock-off arrangement would be necessary, and this would further complicate the machine. In 45 case the upset blanks should stick to the dies a knock-out will of course be employed. By the arrangement shown two stock-rods will be simultaneously fed to the machine, cut off, and upset at a single stroke, and by providing additional feeding-grooves in the rolls, 50 gripping-recesses in the holding-dies, and upsetting-punches it would be possible to work up more than two rods at a single stroke. The construction, however, does not prevent 55 a single stock-rod being worked up, if desired.

To enable the feeding of the stock-rod to the machine to be interrupted, one of the feeding-rollers is so mounted that it can be moved away from the other one, thus loosening the grip of the rollers on the rod. I have shown the shaft of one of said rollers—as, for instance, the shaft 24—mounted in stationary bearings 36, both at its upper and lower end, while the other shaft 23 is mounted at its upper end in the movable bearing 37 and at its lower end in the rocking bearing 38, which is pivoted at 39, so that the upper end of the

shaft and the roller 2 can swing away from the roller 3. A very slight movement only is necessary in order to loosen the feeding-grip on the stock-rod, and as the pivot 39 is very near the lower end of the shaft it results in such a slight movement of the bevel-gear 25 as not to interfere with its proper mesh with the gear 27. The roller 2 is held against the roller 3 by means of a cam-lever 40, suitably pivoted in the frame and having one arm pressing against the bearing 37, while the other arm is connected by a rod 41 to lever 42, mounted in the lower part of the frame and provided with a suitable spring or weight 43, which tends constantly to hold the two feed-rollers together. The outer end of the lever is provided with a treadle 44, whereby the load 43 can be overcome, so that the roller 2 will of its own accord swing away from the roller 3. In this manner the feeding of the stock-rod to the machine can be stopped whenever desired.

The gripping dies or jaws 7 and 8 are preferably formed as rectangular blocks, as shown in Figs. 3 and 4, each of which is provided with a plurality of gripping-recesses 35 on each of its four sides, so that when the recesses on one side become worn the dies can be turned to present a new face, as will be readily understood. The movable die 8 is clamped in a recess in the upper end of the lever 46, pivoted on the stud 47, which lever has connected thereto the toggle-links 21. The stationary die 7 rests upon a plate 49 and is clamped thereagainst by the top setscrew 50 and is adjusted horizontally by the backing-screw 51, extending through the frame and having on its outer end the hand-wheel 52. It is essential that the gripping-recesses 35 in the two dies correspond exactly to each other; otherwise there will be a tendency to form a ridge or fin on the two sides of the blank. By reason of the great strain to which these dies are subjected they easily get out of adjustment, so that frequent stoppages of the machine are necessary in order to adjust them. One of the features of my invention is to provide adjusting means for this purpose which can be operated without stopping the machine. I have therefore shown the plate 49, upon which the stationary die 7 is seated, resting on an eccentric-pin 54 on the inner end of a shaft 55, which extends through the frame and is provided at its outer end with suitable means whereby it can be rotated, such as the worm-segment 56, which is engaged by a worm 57, having thereon a hand-wheel 58 for turning the same. This hand-wheel is on the outside of the machine where it is readily accessible when the latter is in operation, so that by means of it the eccentric-pin 54 can be turned to raise or lower the stationary die 7, the top screw 50 being of course adjusted simultaneously therewith. The vertical adjustment for the movable die 8 is secured by mounting the stud 47 eccentrically in a sleeve 60, which is rotatably

mounted in the frame and which is provided at its outer end with the gear 61, with which meshes a pinion 62 on a shaft 63, projecting outside of the frame and provided at its outer end with a hand-wheel 64, which likewise is readily accessible, so that the sleeve 60 can be turned to adjust the movable die vertically without stopping the machine.

The movable die, as heretofore stated, forms the movable jaw of the shears, it being moved by the toggle-links 21 across the openings 6 in the shearing-plate 5, thus shearing off the stock-rods and carrying the cut-off portions sidewise against the stationary die 7. This movement is clearly shown in Figs. 9, 10, and 11, Fig. 9 showing the gripping-dies open, Fig. 10 showing the movable die in the act of cutting off a blank, and Fig. 11 showing the blank carried over against the stationary die and the upsetting-punch having headed the blank. In this operation it is of course essential that the movable die 8 have a dwell or pause, so that it will hold the blank against the stationary die sufficiently long to enable the heading-punch to properly upset the blank. In order to secure this dwell or pause and also to prevent breakage in case a distorted blank is in the dies, I provide a yielding or flexible connection between the crank 19 and toggle-links 21. As shown in the drawings, the connecting-rod 20 is provided with a shoulder or nut 65^a and passes through a sleeve 65, connected at the knuckles of the toggle-links. To the outer end of said connecting-rod is secured a cap 66, between which and a similar cap 67, formed on the sleeve 65, is interposed a strong compression-spring 68. This spring is so adjusted that before the crank 19 has reached its full outer throw the movable die 8 will have been carried against the stationary die, and in the further movement of the crank the said spring will be further compressed, thus permitting the movable jaw to remain stationary until the crank has passed so far beyond its outer throw as to bring the shoulder 65^a against the sleeve 65. In this manner a sufficient pause or dwell of the movable jaw is secured by means of a simple crank or eccentric.

The stock-gage 9 is preferably disposed in a vertical position and secured to a rocking shaft 70, suitably mounted in the frame of the machine. This shaft is screw-threaded, as shown at 71, and is surrounded by the internally-threaded worm-wheel 72, with which meshes a worm 73 on the inner end of a shaft 74, the outer end of which is provided with a hand-wheel 75 or the like outside of the frame, so that it is readily accessible in order to adjust the position of the stock-gage without stopping the machine. By turning this hand-wheel the rod 70 will be moved longitudinally, and thus vary the position of the gage to vary the length of blank to be cut from the stock-rods. This gage must of course lie in the path of movement of the stock-rods while the latter

are being fed into the machine; but it must be moved out of the way before the upsetting-punch is projected. The gage therefore is provided with the depending arm 76, having the horizontal finger or stud 77, which lies in the path of movement of the lever 46, which carries the movable die, so that as the latter moves inward to shear off the stock-rod the lever will contact with the finger 77 and rock the gage 9 and move the same out of the path of the upsetting-punch. The finger 77 is of considerable length, as shown, so that it will permit the longitudinal adjustment of the gage and still be in the path of movement of the lever 46. In order to again rock the gage into its vertical position when the movable die 8 recedes, it may be provided with a suitable counterweight which will swing it to the vertical position; but I prefer to connect the finger 77 to the lever 46 by means of a light spiral spring 78, so that when the lever 46 moves outward the spring will pull the gage back to its vertical position.

The reciprocating head 11 is provided at its forward end with a yoke 80, and in said yoke are the top and bottom saddle-blocks 81, between which the plurality of upsetting-punches are held and one of which—as, for instance, the top block—is adjustable by the screw 82 to clamp the punches in place. These punches have their contact-faces flattened off, as shown at 83, and the saddle-blocks 81 are provided with substantially V-grooves, so that the punches will always be held in perfect alinement and without danger of becoming displaced.

By reason of the constant severe shocks to which the upsetting-punches are subjected they soon get out of adjustment, so that they no longer move into close contact with the gripping-dies, and thus permit the formation of a fin at the head of the upset article. It is therefore necessary to frequently adjust these punches, and in prior machines this could only be done by stopping the machine and placing washers or shims behind the punches. I provide an adjustment, however, which is practically automatic. To this end the head 11 is provided with a chamber or cylinder 85, in which moves a backing-block 86, which is practically a piston, and the outer end of which serves as an abutment against which the rear ends of the upsetting-punches rest, although, if desired, the punches might be integral with the piston. The chamber or cylinder 85 communicates by means of a port or passage 87 with a chamber 88, and in said port or passage is the check-valve 89, which is so arranged that it will open to permit liquid to pass from the chamber 88 to the chamber 85, but not in the opposite direction. These chambers are practically full of oil, water, or other incompressible liquid. The piston 86 is constantly pressed outward by a spiral spring 90, arranged in the chamber 85. The outward movement of said piston is limited by a forked lever 91, which

straddles the forward end of the piston and is pivoted at its lower end at 92 and has its upper end provided with the adjusting-screw 93, the end of which contacts with some stationary part of the head 11, such as the yoke 80. Should the heading-punches get out of adjustment, so that it is necessary to move them slightly forward, the screw 93 will be slightly turned, so as to permit the spring 90 to force the piston 86 out a short distance. The suction thus created will raise the check-valve 89, permitting liquid to pass from the chamber 88 into the cylinder 85. The check-valve 89 will prevent the impact of the upsetting-punches against the blank from driving the liquid back into the chamber 88, and as the liquid is incompressible a practically non-yielding backing for the punch is provided.

It frequently occurs that the cut-off blank becomes wedged in the machine in such a manner that it will prevent the upsetting-punches from reaching the limit of their outward stroke. When this happens, all of the parts of the machine are put under such tension or strain that it is practically impossible to turn the same backward to release the blank, thus occasioning much delay and annoyance. To avoid any delay for this reason, I provide a relief-passage 95, leading from the cylinder 85 to the chamber 88, which relief-passage is controlled by the screw-valve 96. By merely opening said valve the liquid-pressure in the cylinder 85 can be released, thus allowing the upsetting-punches to recede and taking the strain off the machine, so that it can be turned backward.

The operation of the machine is in the usual and ordinary way and will be readily gathered from the foregoing description. By means of my improvements a plurality of stock-rods can be simultaneously fed to the machine, cut into sections, and upset, and said upset sections will of their own accord fall out of the machine as soon as the gripping-dies are opened. The feeding mechanism can be stopped whenever desired by merely pressing the treadle 44, which will permit the feeding-rolls to separate. The stock-gage can be adjusted to vary the length of blank by merely turning the hand-wheel 75. The gripping-dies can be adjusted if they get out of alignment by suitably turning the hand-wheels 58 or 64, as the case may be, and the adjustment of the punches is secured by merely turning the adjusting-screw 93. All of these adjusting means are readily accessible on the outside of the machine and are not in the path of any moving part thereof, so that the adjustment can be effected without stopping the machine. As a consequence the machine can be kept in practically continuous operation, and as a plurality of stock-rods can be worked up simultaneously the output is increased three or four fold over prior machines.

Furthermore, should any accident happen to the machine, so that it becomes stalled with the parts under great tension, by merely

opening the relief-valve 96 the tension can be relieved and the machine turned backward. The means for adjusting the punches is practically self-controlled, and this feature of the invention is applicable to any machine having a reciprocating head carrying tools of various kinds which must be projected to a uniform distance.

What I claim as my invention, and desire to secure by Letters Patent, is—

1. In a metal-upsetting machine, the combination with a stationary shearing-die, of a movable shearing and gripping die, a co-operating gripping-die, said gripping-dies opening on a vertical line and having a plurality of gripping-recesses, means for opening and closing said dies, a pair of vertical rollers having a plurality of feeding-grooves therein, a reciprocating head movable toward and from said shearing and gripping dies, and a plurality of upsetting-punches carried thereby.

2. In a metal-upsetting machine, the combination with shearing and gripping dies for the blank and an upsetting-punch, of a pair of positively-driven feed-rollers mounted on vertical shafts, a rocker bearing at the lower end of one of said shafts, a cam bearing against the upper end thereof, and movable pressure means for holding said cam against said shaft.

3. In a metal-upsetting machine, the combination with shearing and gripping dies for the blank and an upsetting-punch, of a pair of positively-driven feed-rollers mounted on vertical shafts, a rocker bearing at the lower end of one of said shafts, an arm bearing against the upper end of said shaft, and a weighted lever connected to said cam-arm for holding the roller on said shaft against the opposite roller.

4. In a metal-upsetting machine, the combination with shearing and gripping dies for the blank and an upsetting-punch, of a stop or gage for determining the length of the blank, a longitudinally-movable rod to which the same is secured, said rod being provided with screw-threads, an internally-threaded gear working thereon, and means for rotating said gear, thereby moving said rod longitudinally.

5. In a metal-upsetting machine, the combination with shearing and gripping dies for the blank and an upsetting-punch, of a vertically-disposed stop or gage, a rocking bearing therefor, and connections between the movable jaw and the gage for rocking the same.

6. In a metal-upsetting machine, the combination with a stationary and a movable gripping-die for the blank, of an upsetting-punch, a stop or gage, a rocking bearing therefor, an arm on said gage adapted to contact with the movable die, and a spring connected to said arm and die moving means.

7. In a metal-upsetting machine, the combination with stationary and movable shearing and gripping dies, of an upsetting-punch, a stop or gage, a rocking bearing therefor,

means for adjusting said gage longitudinally, and an elongated finger on said gage and adapted to contact with the movable die.

8. In a metal-upsetting machine, the combination with an upsetting-punch, of a stationary gripping and shearing die, a movable gripping and shearing die, a lever in which the latter is mounted, a pivot for said lever on which it swings toward and from the other die, and means for adjusting the pivot of said lever vertically.

9. In a metal-upsetting machine, the combination with an upsetting-punch, of a stationary gripping and shearing die, a movable gripping and shearing die, a lever in which the latter is mounted, and an eccentrically-mounted pivot on which said lever is mounted and on which it swings toward and from the other die.

10. In a metal-upsetting machine, the combination with an upsetting-punch, of a stationary gripping and shearing die, a movable gripping and shearing die, a lever in which the latter is mounted, a pivot for said lever on which it swings toward and from the other die, an eccentric-sleeve surrounding said pivot, and means for rotating said sleeve.

11. In a metal-upsetting machine, the combination with an upsetting-punch, of a stationary gripping and shearing die, a movable gripping and shearing die, a lever in which the latter is mounted, a pivot for said lever on which it swings toward and from the other die, an eccentric-sleeve surrounding said pivot, a hand-wheel located outside of the machine-frame, and connections between the same and said sleeve for rotating the latter.

12. In a metal-upsetting machine, the combination with an upsetting-punch, of a movable gripping-die, a stationary gripping-die, bearings for the latter in which the same can be moved vertically, an eccentric upon which said stationary die rests, and means for rotating said eccentric.

13. In a metal-upsetting machine, the combination with an upsetting-punch, of a movable gripping-die, a stationary gripping-die, adjustable means bearing on top of the same, an eccentric upon which said die rests, and means for rotating said eccentric.

14. In a metal-upsetting machine, the combination with the upsetting-punch, of a movable gripping-die, a stationary gripping-die, an eccentric upon which the same rests, a worm-segment connected to said eccentric, and a worm and hand wheel for operating said segment.

15. In a metal-upsetting machine, the combination with the gripping-dies one of which is movable, toggle-links for actuating the same, a crank or eccentric, a rod connected to said crank and extending beyond the toggle-links and having a shoulder on its extended portion, and a compression-spring between said shoulder and the toggle-links.

16. In a metal-upsetting machine, the combination with the gripping-dies one of which

is movable, toggle-links for actuating the same, a sleeve connected to the knuckle of said toggle-links, a crank or eccentric, a rod connected to said crank and extending through said sleeve and provided with a shoulder near its end, and a compression-spring between said shoulder and said sleeve.

17. In a metal-upsetting machine, the combination with the gripping and shearing dies for the blank, of a reciprocating head, an upsetting-punch movably mounted therein, means for limiting the outward movement of said punch, and a self-adjusting abutment in said head against which said punch rests.

18. In a metal-upsetting machine, the combination with the gripping and shearing dies for the blank, of an upsetting-punch, a reciprocating head therefor, means for pressing the punch outward, a stop for limiting the outward movement thereof, and non-yielding means for preventing the inward movement of said punch.

19. In a metal-upsetting machine, the combination with the gripping and shearing dies for the blank, of an upsetting-punch, a reciprocating head in which the same is mounted, a spring for forcing the punch forward, an adjustable stop for limiting the forward movement thereof, and non-yielding self-adjusting means for preventing the punch from moving backward.

20. In a metal-upsetting machine, the combination with the gripping and shearing dies for the blank, of an upsetting-punch, a reciprocating head in which it is mounted, means for moving the punch forward, an adjustable stop for limiting the forward movement thereof, and automatic means for admitting fluid behind said punch.

21. In a metal-upsetting machine, the combination with the gripping and shearing dies for the blank, of an upsetting-punch, a reciprocating head in which the same is mounted, said head being provided with a cylinder or chamber, a piston therein against which said punch rests, means for projecting said piston outward, and a fluid-passage to said chamber having a check-valve therein.

22. In a metal-upsetting machine, the combination with the gripping and shearing dies for the blank, of an upsetting-punch, a reciprocating head in which it is mounted, said head having a chamber or cylinder, a piston therein against which said punch rests, a spring for projecting said piston outward, a forked lever for limiting the outward movement of said piston, a screw for adjusting said lever, and a fluid-passage to said chamber provided with a check-valve.

23. In a metal-upsetting machine, the combination with the gripping and shearing dies for the blank, of an upsetting-punch, a reciprocating head in which the same is mounted, said head having a chamber, a piston therein against which the punch rests, means for projecting the piston outward, a fluid-passage to said chamber having a check-valve

therein, a relief-outlet from said chamber, and a valve for controlling the same.

24. In a metal-upsetting machine, the combination with the gripping and shearing dies for the blank, of a reciprocating head, two or more punches having flat contact-surfaces, grooved or V-shaped saddle-blocks in said head and embracing said punches, and means

for clamping said punches and saddle-blocks in said head.

In testimony whereof I, the said RUDOLPH G. BEKER, have hereunto set my hand.

RUDOLPH G. BEKER.
